ROTARY ENGINE

Filed Sept. 21, 1938

5 Sheets-Sheet 5

ders are of greater length than the chests 2, 3 and 4, but of less length than chest 1. The chests and cylinders are arranged in endwise abutting relation and retained in such position by spaced tie bolts 8 carrying clamping nuts 9 bearing against the outer end faces of the chests 1, 4. The chest 1 (Figure 2) has a pair of spaced normally closed openings 10 at its top and a pair of spaced normally closed openings 10a at its bottom for access thereto. The chests 2, 3 and 4 are provided with normally closed openings 11 at their tops and with normally closed openings 12 at their bottoms for access thereto. The chest 1 is of a different construction with respect to the construction of the chests 2, 3, 4. The chests 2, 3 are of different construction with respect to the construction of the chests 1, 4 and the chest 4 is of a different construction with respect to the construction of the chests 1, 2 and 3. The cylinders 5, 6 and 7 are of like construction and of a construction different from any one of the chests. The chests 1, 2, 3 and 4 each include, as best shown in Figure 6, an annular steam jacket wall 13, a pair of steam inlet manifold sections 14, 15 formed with steam inlets 16, 17 respectively for a cylinder. The chests 1, 2, 3 and 4 include a pair of spaced bearings 18, 19, for a purpose to be referred to and an exhaust controlling valve cylinder 20 arranged between the bearings 18, 19. Each chest includes a pair of end walls integral with the wall 13 thereof. The end walls for the chest 1 are designated 1a, 1b; those for the chest 2 at 2a, 2b; those for the chest 3 at 3a, 3b; and those for the chest 4 at 4a, 4b. The wall 1a of chest 1 is provided with a threaded opening 22 for attaching thereto an exhaust pipe not shown, a steam supply opening 23 above the opening 22 and an opening 24 above the opening 23 for a purpose to be referred to. The chest 1 has an integral part thereof to provide therein a supply controlling valve cylinder 25 open at each end and with which the steam intake manifold sections 14, 15 (Figure 5) thereof are integral. The opening 23 communicates with the cylinder 25 and the latter is provided with a pair of spaced superposed steam supply openings 26, 27 for selectively establishing communication between the intake manifold sections 14, 15 of said cylinder. Each of the chests 50 has an integral part thereof providing therein an exhaust controlling valve cylinder 20. The wall 1b of chest 1 has a pair of superposed spaced exhaust openings 28, 29 which open into its cylinder 20. The chest 1 has integral with the inner face of its wall 1a, its cylinder 25, its wall 1b, and its manifold sections 14, 15 a pair of wall forming portions 30 which are also integral with the wall 13 and provide a pair of spaced heads 32 forming continuations of a steam jacket constituting an exhaust manifold to be referred to. The manifold sections 14, 15 of chest 1 open at their rear ends through the wall 1b of chest 1. The walls 2a of chest 2 are formed with a pair of superposed spaced exhaust openings 33, 34 which communicate with the cylinder 20 of such chest. The wall 2b of chest 2 is formed with a pair of superposed spaced exhaust openings 35, 36 which communicate with the cylinder 20 of such chest. The wall 3a of the chest 3 is formed with a pair of superposed spaced exhaust openings 37, 38 which communicate with the cylinder 20 of such chest. The wall 3b of chest 3 is formed with a pair of superposed spaced exhaust openings 39, 40 which communicate with the cylinder 20 of such chest. The wall 4a of

chest 4 is provided with a pair of spaced superposed exhaust openings 41, 42 which communicate with the cylinder 20 of such chest. The manifold sections of the chest 2 have a portion of their ends opening through the end walls of such chest as at 5a. The manifold sections of the chest 3 have a portion of their ends opening through the end walls of such chest as at 5b. The manifold sections of the chest 4 have a portion of their inner ends opening through the wall 4a and have their outer ends closed by wall 4b.

The cylinders 5, 6, 7 include annular body portions 43 which constitute steam jacket wall sections. The construction of each cylinder is best shown in Figure 7 and attention is directed thereto. Each cylinder has arranged and supported within its body portion a pair of oppositely disposed inner sidewise communicating segmento-cylindrical rotor chambers 44, 45 which are partly closed at their ends by the opposed end walls of the steam chests between which the cylinder is arranged. The chambers 44, 45 are suspended within the body portion 43 by the spaced ribs 46. Integral with the chamber 44 is a steam inlet manifold section 47 and integral with the chamber 45 is a steam inlet manifold section 48. The manifold sections 47, 48 form flush continuations of the open end portions of the manifold sections 14, 15, and establish communication respectively between the manifold sections of the chest 1 with the manifold sections of the chest 2, the manifold sections of the chest 2 with the manifold sections of the chest 3, and the manifold sections of the chest 3 with the manifold sections of the chest 4. The steam inlets 16 open into the chambers 44. The steam inlets 17 open into the chambers 45.

Arranged in each pair of communicating rotor chambers are the rotors 48, 49 provided with pockets 50, 51 respectively and with pistons or vanes 52, 53 respectively. The rotors of each pair are disposed horizontally and in inner, edgewise alignment. The rotors are similar in construction and function in the same manner as the pair of rotors set forth in the patent aforesaid, with the exception that the pistons are mounted on shims 54 and provided with oil grooves 55. The rotors are provided with oil grooves 55a which extend from the inner edge 56 to the outer edge 56a of the rotor and in this connection attention is directed to Figure 9.

The rotors are provided with axial openings 57 which provide the inner edges 56. Extending through and fixed to the rotors 48 is a horizontally disposed rotor driven shaft 58. The latter is mounted in the bearings 18 and extends from the bearing 18 in the chest 1 to a point extended rearwardly from chest 4. Extending through and fixed to the rotors 49 is a horizontally disposed rotor driven shaft 59 mounted in the bearings 19 and extending from the bearing 19 in the chest 1 to a point extended outwardly from the chest 5. The shaft 58 extends a greater distance outwardly from chest 4 than the shaft 59 and it is adapted to be connected to a power transmitting shaft.

The rotors are arranged in a pair of banks, one bank formed by the rotors 48 and the other by the rotors 49. The bank formed by the rotors 48 is carried by the shaft 58, and the bank provided by the rotors 49 is carried by shaft 59. The pistons 52 on the rotors 48 are always fixed thereto. When three rotors 48 are employed

they are so mounted on the shaft to position the pistons 120° apart from each other, in a six cylinder engine, the pistons would be placed 60° apart or with respect to a twelve cylinder engine 30° apart. The splines on shaft 58 permit the placing of the rotors at different angles to each other, depending on the number of cylinders used. The statement aforesaid with respect to the pistons 52, rotors 48 and shaft 58 applies to the arrangement of the pistons 53, rotors 49 and shaft 59.

Arranged within the cylinder 25 and controlling the steam supply openings 26, 27 is a steam supply reversing valve 60 having a pair of spaced heads 61, 62 for selectively opening and closing the openings 26, 27 to the manifold sections 14, 15 respectively. Arranged within the valve chambers 29 are exhaust reversing valves 63 for controlling the exhaust openings provided in the steam chests. The valves 60, 63 are connected to squared portions of a common reversing shaft 64 therefor by pivoted stems 65 and crank arms 66. The shaft 64 is journaled in the chests and cylinders and extends inwardly into the chest 1 through opening 24 and has its rear end journaled in the chest 4. The outer end of shaft 64 has connected thereto a reversing lever 67.

The shaft 58 is what may be termed a power take-off shaft forming an element of the three cylinder engine, as shown. One end of the shaft would be machined to meet power take-off requirements. A portion of the shaft will be machined to take on double helical timing gears and roller bearings. The remaining portion of the shaft will be machined to take the required number of rotors and intermediate bearings. The shaft 58 reduces in size from the timing gear section to its other end. The bearing surfaces subject to wear are made oversize to allow for remachining after service wear has taken place. The shaft 58 extends through a gear box 68. The shaft 59 is of the same form as the power take off shaft 58, except that one end of shaft 59 extends into a cap 69 on the gear box 68 and has its other end provided with a socket 69a to take the square or hexagonal end 69b of a shaft 70 for the purpose of driving a governor 71. The shafts 58, 59 and the rotors will be machined with spaced sets of twelve splines 71a to the circumference in order to permit building engines with one, two, three, four, five, six or twelve cylinders with uniformly spaced power impulses. The gear box 68 is secured to the outer end of steam chest 4 and held in proper alignment by suitable holdfast means. The gear box 68 is to be provided with a cover 71b, an oil filler plug 72 and an oil drain plug 73 and an oil gage not shown. The gear box 68 (Figure 12) is formed on its inner side with a pair of annular horizontally aligned bosses 73a, only one shown and on its outer side with a pair of horizontal bosses 73b only one shown. Arranged in the said bosses are bearing structures 74a. The cap 69 is secured to one of the bosses 73b. A cap 75 is secured to the other boss 73b and through which extends the shaft 58. The gear box 68 has arranged therein a worm gear 73c (Figure 20) for service as a cone retaining nut for shaft 59. The bosses 73a align with the bosses 73b. The shaft 58 extends through one pair of aligned bosses, and the shaft 59 is mounted in the other pair of aligned bosses. A stop collar 75a is carried by the shaft 58 for one of the bearing structures 74a.

The spaces between the steam jacket wall section and the wall forming portions of chest 1 and

the spaces between the steam jacket wall sections and the steam inlet manifold sections coact to provide a continuous steam jacket providing for the engine operating at an approximately even temperature. The steam jacket constitutes a pair of exhaust manifolds opening into each other and which are common to the sets of rotor chambers. The steam jacket is common to the intake manifolds and the sets of rotor chambers.

The steam inlet manifold sections of the steam chests are provided with auxiliary steam inlet ports 71. The valve chambers 29 and the valve cylinder 27 are open at each end. A pressure lubricator 78 is mounted on the gear box 68. The drive for lubricator 78 is indicated at 79 and it is operated from worm 73c in gear box 68. Individual lubricator lines 80 lead from lubricator 78 and pass through packing boxes 81 secured to the walls of the chests 2, 3, 4 and the inner wall of chest 1. There are six lubricator lines to the top of the rotor cylinders and six lines to the bottom of the rotor cylinders and they are supported in the steam chests by clips 82 held in position by certain of the assembly bolts. The timing gears 83 are double helical and keyed to the shafts 58, 59. The governor 71 is of the fly-ball spring controlled type. Attached to the wall 1a of chest 1 is a steam inlet valve mechanism 84 controlled from the governor 71. The mechanism 84 has an outlet 85 which registers with the opening 23.

Each rotor assembly has a balancing core for balancing purposes. Additional balancing holes are drilled after all other machining operations are completed and with the pistons assembled on the rotors in order that the assembly may be perfectly balanced. The oil grooves 55 will be arranged at the sides and in the tops of the pistons. The oil grooves 55a will be arranged at the sides of the rotors. Certain of the grooves 55a will register with the inner ends of the oil groove on the sides of the pistons. The grooves 55, 55a are for lubricating and steam seal purposes. The pistons are bored concentric with the circumference and broached splines are on the shafts 58, 59. This construction prevents binding of the rotors due to unequal temperature between the shafts 58, 59 and the engine body.

The steam inlet ports 16, 17 may be machined to subtend any desired angle, within limits at the rotor axis. The auxiliary steam inlet ports 77 are optional with the builder and when used will be of a sufficient size to admit steam at full steam chest pressure for starting purposes and at very slow speeds and yet so small as to admit a negligible amount of steam at normal operating speeds.

The joints between the steam chests and the cylinders are machined male and female and are made steam-tight by suitable gaskets, not shown, the thickness of which may be reduced to compensate for wear on the faces of the rotors and pistons. The shims 54 which are disposed between the bases of the pistons and the periphery of the rotors are to compensate for wear on the tops or outer ends of the pistons. The wall 4b (Figure 12) of chest 4 is formed with a pair of parallel spaced openings 86, only one shown, and a pair of inwardly extended internally shouldered sleeves 87, only one shown which form inward continuations of the walls of openings 86. Mounted in each opening 86 and the sleeve 87 which extends inwardly therefrom is a tubular peripherally shouldered bearing 88 formed with oil seal rings 89 and an oil drain groove 90. The shafts 58, 59 extend through the tubular bearings 75.

68. The sleeves 67 extend from the wall 4a to the wall 4b of chest 4. The shims 54 are provided with notches for registering with the grooves 55, 55a.

5 The governor 71 includes a shaft structure 91 so formed and so connected to shaft 70 to provide for the oscillating of a bell crank 92 (Figure 19) supported from the mechanism 84 and employed for vertically moving a shift rod 93 which in 10 turn operates the operating lever 94 (Figure 18) of the mechanism 84. The lever 94 is employed for adjusting the position of the valve stem 95 of mechanism 84 to control supply of steam at the opening of steam inlet 23.

15 The crank arms 66 are carried by collars 96 (Figures 13 and 14) which are fixed to shaft 64 by set screws 97. The stem 65 for the valve 69 is of less length than the stems for the valves 63. The lower end of lever 67 merges into a collar 98, which is secured to the shaft 64 by a set screw 99. Packing means 100 is provided for the end terminal portions of the bolts 8 (Figure 8). Packing means 101 is provided for that end terminal portion of shaft 64 which carries lever 67 (Figure 11).

20 The structure provided by the connected together chests and cylinders is supported by a pair of oppositely disposed angle-shaped base members 102 which are secured to the ends of such structure by the holdfast means 103.

25 With reference to Figure 15 there is shown a chart provided with the representation of an ideal pressure curve for one unit of the engine when exhausting into the atmosphere. Now referring to Figure 16, let b =angle subtended at the axis of rotor by the arc of the steam inlet port. Let d =angle subtended at the axis of the rotor by the arc of the top of the piston. Let c =angle included at the axis of the rotor by a 30 plane passing thru the two rotor axes and a plane passing thru one rotor axis and the point of intersection of the two cylindrical surfaces of the "cylinder." Let a =angle subtended at the axis of the rotor by the gap. Let e =angle subtended at the axis of the rotor by the arc of the base of the piston 17. This angle also equals the angle subtended at the axis of the rotor by the chord across the points of the gap at the periphery of the rotor. Let R =the radius of the 35 rotor. Let R' =the radius of the cylinders.

40 Then the following statements are true:

$c = \cos^{-1} R/R'$. (R and R' are arbitrary with the builder of the engine.)

$e = d$ plus k where k is a function of c .

45 a is arbitrary with the builder of the engine.

50 Referring to Figure 15, pressures inside the cylinders are platted against the angular travel of the centerline of the pistons with reference to a line joining the points $O-O'$ of the axes of the rotors.

55 Time of steam admission: $c-d/2$

Time of steam cut-off: a plus b plus $c-d/2$

Time of steam exhaust: $360^\circ - (c-d/2 + e)$

60 From the above considerations, it will be seen that this engine can be built to meet a wide variety of pressure cycle characteristics.

65 The splined shafts are so disposed relative to the rotors and the rotor chambers to function for maintaining the centers on the rotors, that is to say each splined shaft not only couples the rotors of a bank in spaced relation, but each shaft also acts to maintain a perfect center for the rotors between the side walls of the rotor chambers.

To operate this engine, place reverse lever 67 70 in position shown in Figure 3. Steam inlet valve

(60-61-62) is then in position shown in Figure 6. Steam entering engine through port 23 passes through chamber 25 and port 26 into manifold 14; thence through port 16 into rotor chamber 45 where pressure is exerted on piston 53 causing rotor 49 to rotate in a clockwise direction and pressure exerted on piston 52 causes rotor 48 to rotate in a counter-clockwise direction. Exhaust steam ahead of the pistons passes out through exhaust port 29 and chamber 20 into steam jacket; thence out of the engine through port 22. Steam pressure is applied to the pistons at boiler pressure during the rotation of the rotors 48 and 49 until inlet ports 16 are covered by rotor 48. Adiabatic expansion of the steam continues to rotate the rotors until the pressure is relieved by the piston's 53 passing exhaust port 29 through which the steam is exhausted. Momentum of the rotors and impulses from adjacent cylinders carry the pistons around to the 20 position shown in Figure 7 again, when the cycle is repeated.

25 To reverse this engine, throw reverse lever 67 over to the right. Inlet valve will then be in such position that boss 61 will close port 26 and boss 25 62 will uncover port 27 and exhaust valve will be in such position that exhaust port 28 will be open and exhaust port 29 will be closed. Steam entering the engine will now rotate the engine in the opposite direction from that previously 30 described.

What is claimed is:

1. In a rotary steam engine, a series of spaced aligned steam chests, a cylinder arranged between each pair of steam chests, spaced means 35 for securing said cylinders and chests together in endwise relation, said cylinders including means providing two sets of aligned rotor chambers, the chambers of one set communicating sidewise thereof with the chambers of the other set, said 40 chests and cylinders having correlated parts providing a pair of steam intake manifolds, one common to and opening into one set of chambers and the other common to and opening into the other set of chambers, said chests and cylinders 45 having coacting parts providing a pair of exhaust manifolds common to said sets of chambers, said exhaust manifolds providing steam jacket forming means for said intake manifolds and chambers, two banks of steam driven rotors, 50 one bank arranged in one set of chambers and the other bank arranged in the other set of chambers, a pair of geared together shafts, each common to a bank of rotors and one constituting a power transmitting means, adjustable control- 55 able means for selectively supplying steam to one of the intake manifolds, and adjustable controllable means for selectively making active one of said exhaust manifolds.

2. In a rotary steam engine, a series of spaced 60 aligned steam chests, a cylinder arranged between each pair of steam chests, spaced means for securing said cylinders and chests together in end-wise relation, said cylinders including means providing two sets of aligned rotor chambers, the 65 chambers of one set communicating sidewise thereof with the chambers of the other set, said chests and cylinders having correlated parts providing a pair of steam intake manifolds, one common to and opening into one set of chambers, 70 said chests and cylinders having coacting parts providing a pair of exhaust manifolds common to said sets of chambers, said exhaust manifolds providing steam jacket forming means for said intake manifolds and chambers, two banks of 75

- steam driven rotors, one bank arranged in one set of chambers and the other bank arranged in the other set of chambers, a pair of geared together shafts, each common to a bank of rotors 5 and one constituting a power transmitting means, adjustable controllable means for selectively supplying steam to one of the intake manifolds, adjustable controllable means for selectively making active one of said exhaust manifolds, and means 10 common to the said pair of adjustable controlling means for simultaneously adjusting them.
3. In a rotary steam engine, a series of spaced aligned steam chests, a cylinder arranged between each pair of steam chests, spaced means for securing said cylinders and chests together in endwise relation, said cylinders including means providing two sets of aligned rotor chambers, the chambers of one set communicating sidewise thereof with the chambers of the other set, said 15 chests and cylinders having correlated parts providing a pair of steam intake manifolds, one common to and opening into one set of chambers and the other common to and opening into the other set of chambers, said chests and cylinders having coacting parts providing a pair of exhaust manifolds common to said sets of chambers, said 20 exhaust manifolds providing steam jacket forming means for said intake manifolds and chambers, two banks of steam driven rotors, one bank arranged in one set of chambers and the other bank arranged in the other set of chambers, a pair of geared together shafts, each common to a bank of rotors and one constituting a power 25 transmitting means, adjustable controllable means for selectively applying steam to one of the intake manifolds, adjustable controllable means for selectively making active one of said exhaust manifolds, and spaced bearings in said chests 25 for said shafts.
6. In a rotary steam engine, a series of spaced aligned steam chests, a cylinder arranged between each pair of steam chests, spaced means for securing said cylinders and chests together in endwise relation, said cylinders including means providing two sets of aligned rotor chambers, the chambers of one set communicating sidewise thereof with the chambers of the other set, said 30 chests and cylinders having correlated parts providing a pair of steam intake manifolds, one common to and opening into one set of chambers, said chests and cylinders having coacting parts providing a pair of exhaust manifolds common to said sets of chambers, said exhaust manifolds 35 providing steam jacket forming means for said intake manifolds and chambers, two banks of steam driven rotors, one bank arranged in one set of chambers and the other bank arranged in the other set of chambers, a pair of geared together shafts, each common to a bank of rotors and one constituting a power transmitting means, adjustable controllable means for selectively supplying steam to one of the intake manifolds, adjustable controllable means for selectively making active one of said exhaust manifolds, and auxiliary steam inlet 40 means for said intake manifolds.
4. In a rotary steam engine, a series of spaced aligned steam chests, a cylinder arranged between each pair of steam chests, spaced means for securing said cylinders and chests together in endwise relation, said cylinders including means providing two sets of aligned rotor chambers, the chambers of one set communicating sidewise thereof with the chambers of the other set, said 45 chests and cylinders having correlated parts providing a pair of steam intake manifolds, one common to and opening into one set of chambers and the other common to and opening into the other set of chambers, said chests and cylinders having coacting parts providing a pair of exhaust manifolds common to said sets of chambers, said exhaust manifolds 50 providing steam jacket forming means for said intake manifolds and chambers, two banks of steam driven rotors, one bank arranged in one set of chambers and the other bank arranged in the other set of chambers, a pair of geared together shafts, each common to a bank of rotors and one constituting a power transmitting means, adjustable controllable means for selectively supplying steam to one of the intake manifolds, adjustable controllable means for selectively making active one of said exhaust manifolds, means common to the said pair of adjustable controlling means for simultaneously adjusting them, and spaced bearings in said chests for said shafts.
7. In a rotary engine, endwise aligned cylinders 55 provided therein and spaced from the walls thereof of two sets of rotor chambers, revoluble power generating rotors within each set of said chambers, means within the cylinders adjacent said chambers providing a pair of intake manifolds, each common to a set of chambers, a pair of exhaust manifolds between said chambers and intake manifolds and the walls of the cylinders and common to said sets of chambers, and said 60 exhaust manifolds opening into each other and, constituting a steam jacket common to said chambers and intake manifolds for maintaining uniform temperature during the operation of the engine.
5. In a rotary steam engine, a series of spaced aligned steam chests, a cylinder arranged between 65

JAMES F. HANDY, 70
Executor of the Last Will and Testament of
Russell P. Glenn, Deceased.
